[57] CLAIM

The ornamental design for a hermetically sealable cover for golf clubs and bag, as shown and described.

DESCRIPTION

FIG. 1 is a front perspective view of a hermetically sealable cover for golf clubs and bag, in a closed position, showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view, with the left side being a mirror image thereof;

FIG. 7 is a front perspective view thereof, in open position.

FIG. 1

FIG. 2

FIG. 3

FIG. 4

FIG. 5

FIG. 6

FIG. 7
